UNITED STATES PATENT OFFICE.

STERLING H. CAMPBELL, OF ST. LOUIS, MISSOURI.

DESIGN FOR A HANGER FOR TROUSERS AND CRAVATS.

Application filed May 25, 1928. Serial No. 26,861. Term of patent 3½ years.

To all whom it may concern:

Be it known that I, STERLING H. CAMPBELL, a citizen of the United States of America, residing at the city of St. Louis, State of Missouri, have invented a new, original, and ornamental Design for a Hanger for Trousers and Cravats, of which the following is a specification, reference being had to the accompanying drawing, forming a part thereof.

In the drawing Figure 1 is a side elevation; Figure 2 an end view; and Figure 3 a top view of my hanger.

I claim:

The ornamental design for a hanger for trousers and cravats as shown.

STERLING H. CAMPBELL.
